ADJUSTMENT MEANS FOR WRENCH-TYPE PLIERS

Homer A. Mead, Turlock, Calif.

Application January 25, 1957, Serial No. 636,322

1 Claim. (Cl. 81—411)

This invention relates to wrench-type pliers in which the work-engaging jaws are adjustable relative to each other so as to be engageable with work pieces of many different sizes.

Such a tool includes jaw shanks crossing each other, one shank having a slot therein provided along one edge with depending notches or cradles, and the other shank having a pivot pin removable along the slot and engageable in seating relation in any selected cradle.

A major object of this invention is to provide a pivot pin and lug combination on said other shank so arranged that a full-circle pin may be used; the pin engaged and supported by a bearing surface extending along a major portion of the length of the pin; and said pin prevented from tipping or being possibly sheared off when the tool is under heavy load.

A further object of the invention is to so dispose the pin-engaging cradles along the slot that the lateral pressures to which the pin is subjected, when the tool is under load, cause said pin to be firmly seated in the related cradle and to be braced and held against any possible tendency of the pin to leave or escape the cradle.

Another object of the invention is to provide an adjustment means for pliers, of the type described, which reduces manufacturing operations and at the same time increases the strength and efficiency of the working parts without any increase in the size of such parts.

It is also an object of the invention to provide a practical and reliable adjustment means for wrench-type pliers, and one which will be exceedingly effective for the purpose for which it is designed.

These objects are accomplished by means of such structure and relative arrangement of parts as will fully appear by a perusal of the following specification and claim.

In the drawings:

Fig. 1 is a side elevation of the improved pliers as engaged with a work piece; the pivot-pin nut being partly broken away.

Fig. 2 is a fragmentary side elevation of the pliers showing the pivot pin in position to allow adjustment of the jaws; the pivot pin nut being removed.

Fig. 3 is an enlarged cross section on line 3—3 of Fig. 1.

Referring now more particularly to the drawings, and to the characters of reference marked thereon, the pliers comprise essentially a pair of separate members, indicated generally at 1 and 2, and arranged in crossing relation to each other.

The member 1 comprises a jaw 3, a flat, relatively wide shank 4 extending from the jaw at an obtuse angle thereto, and a handle 5 projecting from the end of the shank opposite the jaw. A pin 6 is mounted in the shank intermediate its ends and side edges, said pin having a head 7 on one end and a nut 8 on the other end.

Member 2 comprises a jaw 9 opposed to jaw 3, a flat, relatively wide and elongated shank 10 extending from one end of the jaw substantially at right angles

2

thereto, and a handle 11 projecting from the end of the shank 10 opposite the jaw and at an acute angle to the shank in a direction away from the jaw.

The shank 10 is formed with an elongated slot 12, extending lengthwise of the shank and thus substantially at right angles to the jaw 9, and whose width is slightly greater than the diameter of the pin 6. Cut into the edge of the slot furthest from the jaw 9 is a row of semi-circular notches or cradles 13, the radius of each of which is such as to receive the pin 6 with a turning fit, and in any selected one of which the pin seats when the jaws are in an operative position.

Formed on the shank 4 and projecting into the slot 12, and engaging about a portion of the periphery of the pin 6, is an arcuate lug 14. The outer edge of such lug is concentric with the pin 6 and the radial extent thereof is such as to have a running fit with the edge of the slot 12 opposite the cradles 13. This prevents any appreciable movement of said pin 6 out of its seat with a relative swinging movement of the jaws 9 within their range of operation at any set position of the pin in one cradle 13 or another.

The chordal extent of the lug 14 at its outer end is somewhat less than the width of the slot 12, as is clear from Fig. 2, and said lug is shaped so that the trailing edge 15 thereof, relative to the direction of rotation of the corresponding shank and handle required to open the jaws 9, is substantially parallel to jaw 3 and tangent to the adjacent face of the pin 6. The opposed edge 16 of the lug is substantially radial with the axis of the pin. It may be noted here that the nut 8 is preferably on the end of the pin 6 which projects outwardly of the shank 10, and the width of the nut is sufficient to span the slot 12 as well as the cradle in which the pin is engaged. The nut thus of course covers lug 14 as well.

By reason of the above described arrangement it will be seen that various advantages in construction and operation are obtained. By the use of the lug 14, which is integral with shank 4, as shown in Fig. 3, the pin 6 is supported, against the possibility of being sheared by the pressures set up in the pliers when a work piece W is gripped and turned, by the full-length bearing surface provided for the pin by the metal of shank 4 and of the lug 14 which is an integral extension of the shank. This feature also prevents tipping and possible binding of the pin.

The lug—cooperating with the pin—also enables the slot 12 to be as wide as the diameter of the pin, avoiding the necessity of the pin being cut away and thus weakened, as has heretofore been necessary in order for the pin to slide down the slot when making an adjustment.

The lug, moving as a unit with member 1, and being nearly as wide at its outer end as the slot, requires a turn of member 1 relative to member 2 sufficient to dispose the jaws about at right angles to each other before any full disengagement of the pin 6 from any cradle can be effected, as shown in Fig. 2. The lug edge 15—being substantially parallel to the jaw 3—enables the jaws to be thus disposed without jaw 3, which overhangs shank 10, actually contacting said shank. A relatively great range of jaw movement can thus be had with each setting of the pin 6, and without the latter being released from its cradle.

The pin, being full-circle throughout, does not have to be fixed against turning in its shank, and manufacturing and assembling operations are thereby lessened and simplified, and—if desired—a relatively small pin can be used without loss of efficiency, since—as previously stated—the pin is not weakened by being cut, nor is it subject to any shearing strains.

With the lug and pin arrangement as above described, the cradles 13 may be placed quite close together, with only a narrow neck or tip 17 therebetween, and thus giving the maximum number of positions of the pin 6 along the slot 12.

The specific relationship of the edge 15 of the lug to the adjacent surface of the pin 6 provides what is in effect a locating notch to receive and cooperate with each cradle tip 17 as an adjustment of the pin is being made, as indicated in Fig. 2. This provides for a smooth and easy adjustment of the pin into position in any cradle, as the members 1 and 2 are moved relative to each other along the slot 12 to initially dispose the pin in approximate alignment with any cradle.

The cradles 13 depending from the edge of slot 12 furthest from the jaws, pressure acting on the jaws and shanks when the tool is engaged with a work piece and is under load causes the pin 6 to be firmly pressed into the related cradle so that said pin is well seated and braced against possible wobble, or any tendency to work out of the cradle.

From the foregoing description it will be readily seen that there has been produced such a device as will substantially fulfill the objects of the invention, as set forth herein.

While this specification sets forth in detail the present and preferred construction of the device, still in practice such deviations from such detail may be resorted to as do not form a departure from the spirit of the invention, as defined by the appended claim.

Having thus described the invention, the following is claimed as new and useful, and upon which Letters Patent are desired:

In a wrench-type pliers which includes opposed jaws,

shanks projecting from the jaws in crossing relation to each other, and handles projecting from the ends of the shanks opposite the jaws; a pin mounted in and projecting from one shank, the other shank having an elongated slot extending at an angle to its jaw and of a width to receive the pin in clearance relation, and said other shank having a row of notches forming pin-receiving cradles cut in from one longitudinal edge of the slot, and a lug fixed on said one shank and projecting into the slot and embracing a portion of the pin; the outer edge of the lug being concentric with the pin and disposed in close spaced relation to the edge of the slot opposite the cradles when the jaws are in a work-engaging position; the chordal extent of the lug at its outer end being less than the width of the slot; the side edge of the lug which is at the trailing end of said lug when the handle of the corresponding shank is swung in a direction to open the jaws being substantially parallel to the working face of the corresponding jaw and tangent to the pin, while the opposite side edge of the lug is substantially radial with the axis of the pin; said other shank, between adjacent cradles, providing relatively narrow tips along the slot each adapted to enter the recess provided between said radial lug edge and the adjacent face of the pin to initially locate the pin relative to an adjacent cradle.
